SUPPORT FOR TRANSMISSION LINES

Application filed May 25, 1925. Serial No. 32,711.

This invention relates to electrical transmission lines and especially to wooden supports therefor and has for its object the provision of means whereby advantage may be taken of the insulating properties of wood supports for the lines and, at the same time, utilize means for protecting the structure against lightning.

The invention is exemplified in the combination and arrangement of parts shown in the accompanying drawings and described in the following specification and it is more particularly pointed out in the appended claims.

In the drawings—

15 Fig. 1 is an elevation of a wood pole showing one embodiment of the present invention applied thereto.

Fig. 2 is a view looking from the right of Fig. 1.

20 Fig. 3 is a view similar to Fig. 1 showing another embodiment of the present invention.

Fig. 4 is an elevation showing another form of the invention.

25 Fig. 5 is a side elevation of the embodiment shown in Fig. 4.

Fig. 6 is a view similar to Fig. 5 showing a side elevation, of a modification.

On transmission lines it is common practice to use wood poles or towers for carrying the insulators and high voltage conductors. These wood poles are used for practically all voltages from very low voltages to extremely high voltages. Practically the only

35 time a transmission line is subjected to extremely high voltages is during lightning storms or for high frequency or transient conditions on the line. While a wood pole will usually not withstand a high voltage for any length of time where the conductor is directly on the wood, under high frequency conditions where the conductor is supported on an insulator it will withstand a very high voltage and is a comparatively effective insulator. If

40 the insulation of the pole under the highest

voltage conditions existing on the line can be added to the insulator, a very high degree of insulation may be obtained.

Where a wood structure already exists it is desirable to make use of this insulation for the insulation in the structure for the most severe conditions may be even greater than that furnished by the insulator itself unless the latter is of very large size. It will be seen that if the insulation of the pole or wood structure can be utilized, it is of very great economic importance. As the flash-over voltage of the system is increased, the number of arcs to ground will be rapidly diminished. From this it is evident that where effective use of the wood structure may be made, a line of a very high degree of reliability may be installed at comparatively low cost. It is also desirable to utilize the insulation in wood structure, particularly where pin type insulators are used in order to reduce the arcs to ground which may be caused by birds, squirrels, straw or weeds shunting out the insulation furnished by the insulator. It is evident that where the insulation of a wood structure is utilized that the entire insulation cannot be cut out by birds, although the path around the insulator may be readily shunted by a bird or squirrel, or by small objects such as straw or weeds blowing along the conductor up to the insulator.

In many localities it is not necessary to provide any protection for the wood structure. In other sections, however, the storms may be so severe that lightning will shatter or destroy the supporting wood structure. This can be eliminated by running a ground lead or lightning rod along the pole. This, however, practically converts the structure into a steel structure, particularly where the insulator support is tied into the ground lead electrically so that the advantage of the insulation in the wood structure is lost.

In this invention it is desired to utilize the insulation furnished by the wood structure

and, at the same time, eliminate the danger of shattering the same. This may be accomplished in different ways, although the principal may be the same.

5 Figure 1 shows a wood pole 10, upon which cross arms 11 are mounted, supporting insulators 13. A ground wire 14 is supported and insulated by an insulator 15 and extends from pole to pole along the line. The conductors 16 10 carrying current are supported by the insulators 13 in the usual manner.

If in the ordinary practice the ground wire is carried down along the pole, a discharge will tend to take place from the conductors 16 15 to the braces 17 and thence to ground through the ground lead which would be in contact or very close to these braces. By moving the ground lead 18 out from the pole, but in the direction of the line, it will be possible largely 20 to eliminate the short circuit of the insulation furnished by the pole. This is shown to better advantage in Figure 2. While this method has been used quite effectively, it still does not make use of the full insulation of the 25 pole, as the voltage which the conductors will carry is limited by the voltage which will establish an arc between the conductor and the ground lead 18. While it would be possible more fully to utilize the insulation of the pole 30 by providing greater clearance between the conductors 13 and the ground lead 18, this greatly increases the cost of the structure, tends to increase bending moments on the arm and torsional moment on the structure. In 35 addition, the arcing voltage does not increase in proportion to the distance, but falls off quite rapidly for the greater distances so that the method is rather inefficient.

In the present invention, a high flash-over 40 voltage is obtained, particularly for high frequency conditions with rather small clearances, which makes it applicable not only to new lines, but it can be used for improving the effective insulation of existing lines without changing clearances.

The ground or static wire 14 will tend to carry off the charge of lightning and may otherwise dissipate the energy of the surge. This will travel along the ground wire 14 and 50 to ground through the ground or earth connection 18. Since the lead 18 is at ground or earth potential, the electrical stress which may be placed on conductors 13 will either be limited by the insulation provided by the pole, 55 by the structure and the insulator 15 supporting the ground wire or by the break-down of the air between the conductor 16 and the ground lead 18. It is comparatively easy to use a large enough insulator 15 for supporting 60 the ground wire 14 that the limit in voltage for severe high frequency conditions will be the break-down of the air between the conductor 16 and the ground lead 18. As pointed out, it is exceedingly costly to increase the 65 flash-over voltage by increasing this distance.

Since a single insulator 15 tends to increase the effective insulation for all conductors mounted on the structure, it is quite efficient. In order to increase the voltage which the conductors will carry without arcing to ground, 70 it is proposed to equip the conductor adjacent the ground lead 18 with an insulated control or conductor cage shown in previous Patents Nos. 1,611,871 and 1,664,100. This tends to control the electrostatic field and permits a 75 higher high frequency voltage on the line before discharge will occur between the conductor and the ground lead 18. Where there are several conductors on the structure they may set up a very strong field so that a discharge 80 tends to start from the ground lead 18 rather than conductor 16. This is particularly true where conductors 16 are of large diameter and the ground lead 18 of small diameter. Under conditions of this kind, flashing or 85 discharge voltage may be increased by applying a conductor cage to the ground lead or by covering same with insulation, such as a porcelain or fibre tube or even rubber or other insulation which will withstand the weather. 90 The ground lead being at earth potential and generally very much below the corona point, may be simply wrapped with varnished cambric.

Another effective method of preventing 95 discharge from the ground lead 18 where the field is quite strong, is by the use of insulated controls 20 or insulation on the conductor as shown by 19. To prevent discharge from the conductor insulated controls 21 are placed 100 so as to raise the discharge voltage between the conductor 16 and the down lead 18. The discharge voltage between the conductor and down lead may be raised by increasing the effective diameter of the conductor by a cage 105 having an approximately uniformly distributed roughness, by an insulated tube or by insulated controls. The insulated control is shown at 21, conductor cage at 22 and insulation over the conductor at 23. The effectiveness of the combination depends upon the relative insulation furnished by the structure, insulators, the size of conductors, ground lead and the clearance between conductors and ground lead. In many cases the 110 flash-over voltage for severe high frequency surges may be easily doubled compared to conditions where the ground lead simply runs down the pole. In addition, it may easily increase the flash-over voltage by a 115 very appreciable percentage where the ground lead is brought down away from the pole 120 between the conductors.

In many types of existing construction, the flash-over voltage may be easily increased 125 50% by the application of insulated controls to the conductor or conductor and ground wire over that where no insulated control is applied to either.

Another method of accomplishing the 130

same results which reduces the number of insulated controls necessary is to use construction shown in Figure 3. The ground lead 25 may run to a stub pole 26 and guy 27 which is fastened to an earth anchor 28. With this construction, it is possible to keep the ground lead taut and utilize it for guying, particularly where the ground wire insulator 29 is replaced by a suspension or strain insulator 30. The ground or static wire in either case would be at 31. Where the strain insulator 30 is used, ample clearance would, of course, be provided by leaving off the cross arm or raising the point of attachment high enough so that flash-over would not occur between the cross arm or braces and the ground wire 13 or the down lead 25. Both the strain insulator 30 and the ground wire insulator 29 may be used together, although in general one or the other is all that is necessary. Where the strain insulator is used, heavy bending moment is eliminated from the pin insulator 29. If no guying is necessary, the ground lead 25 may be attached to the conductor 31 some distance out from the insulator. If, however, mechanical support is necessary, it is usually necessary to bring the ground lead down in the plane of the structure. It is evident that there is likely to be a strong tendency to cause discharge from the conductor 33 to the ground lead 25, particularly under high frequency conditions. The flash-over or arc-over voltage between the conductor 33 and the ground lead 25 would limit the voltage which may be applied to the system. By the use of insulated controls 34 so as to raise the flash-over voltage between the conductor 33 and the ground lead 25, a very much higher flash-over voltage can be placed on the conductors without causing an arc to ground. Where the field set up by the conductor and controls is quite strong or the voltage very high, discharge may be started from the ground lead 25, particularly where the latter is small in diameter.

The voltage at which this discharge will start can be materially increased by the use of a conductor cage, insulated control or the application of insulation as previously explained and as indicated by the cage 35.

A somewhat different modification is shown in Figure 4. In this instance the circuit is composed of four conductors 36 mounted on two structures. While three conductors only may be used for the three phase transmission circuit, the fourth conductor provides a spare and permits of repairs or may be used in case of failure of one of the other conductors. Where a high degree of insulation is possible, the fourth conductor circuit or even a three conductor circuit may provide a higher degree of reliability than two circuits having lower insulation and the cost will be very much less.

It is apparent from the above discussion that one of the chief difficulties in utilizing the insulation of the wood structure is to prevent discharge between conductor and the ground lead, particularly where a ground or static wire is used. In Figure 4 a type of construction is shown which gives good clearance for the conductor, good mechanical strength and reduces the number of ground leads. The ground or static wire 37 from the two structures may be cross connected by the lead 38 and the earth or ground connection made through the down lead 39. Arcing voltage between conductors 36 located below the cross lead 38 may be raised by the application of insulated controls 40 which, with the field set up by the insulator, may be quite effective in raising the flash-over voltage. If the ground lead 38 is near the top of the insulator support, it may be advisable to use an insulated control 41 to prevent discharge from the charging current between the insulator support and the lead 38. In general, however, this clearance may be made quite effective. Where the cross lead is small or the field set up by the conductors 36 tends to start discharge from the lead 38, the discharge voltage from the lead may be raised by the insulation, an insulated control or a cage, as previously explained. This is indicated by 42.

It is usually advisable to bring the ground lead down some distance out from the structure so as not to shunt insulation furnished by the wood structure. Discharge between the conductors 36 and the down lead 39 may be prevented by insulated controls as previously explained. The discharge voltage of the down lead 39 may be raised by covering the down lead with insulation 44, by the application of insulated controls 47 or conductor cages 48 as previously explained. It is evident that the down lead may be brought down outside of or between the structure by a lead 45. This latter method is very efficient where there is considerable clearance between the two structures. Where the clearance is large, no additional means may be required. It is evident that by controlling the distance or flash-over between the ground lead and conductors or attachments that this clearance may be used as a safety valve to control the voltage which may be applied so as not to damage the wood structures under very severe conditions. In this case it may be advisable to provide some arcing protection for the ground lead such as coiling the wire 46. The coil may be used to increase the effective diameter and the voltage at which discharge occurs from the ground lead in a strong field, or may be used to increase the effective diameter of the conductors themselves and to protect same from power arcs.

Various types of structures may be used without changing the principle. In this con-

reaction it may be said that structure made from wood poles presenting a narrow face to the conductor make the problem of increasing the flash-over voltage much more simple, as it is only necessary to prevent discharge from the conductor for a comparatively short distance.

I claim:

10. The combination with a wood support of a high potential transmission line carried on said support, a ground wire carried by said support, a lead connected with said ground wire, and a flux control device for reducing the tendency to discharge between said transmission line and lead.
15. In combination a wood support for a high potential transmission line, an insulated ground wire on said support, a lead from said ground wire spaced away from said support, and a flux control member on said lead.
20. The combination with a high potential transmission line of a wood support for said line, a ground wire mounted on said support, a lead from said ground wire spaced away from said support, and a flux control device disposed in the field adjacent said lead and line.
25. The combination with a high potential transmission line of a support for said line, a ground wire mounted on said support and insulated therefrom, a lead extending to ground from said ground wire and passing said transmission line in spaced relation thereto, and a flux control member on said lead adjacent said transmission line for minimizing the tendency to discharge between said line and lead.
30. The combination with a high potential transmission line of a support therefor, an insulated ground wire on said support, a lead extending from said ground wire in spaced relation to said support and passing said transmission line in spaced relation thereto, and a flux control member on said transmission line for controlling the field in the vicinity of said lead.
35. In combination a high potential transmission line, a wood support for said line, an insulator for attaching said line to said support, an insulated ground wire on said support, a lead from said ground wire extending to ground in spaced relation with said support and passing said transmission line in spaced relation thereto, and flux control devices on said lead and transmission line for preventing flash-over from said transmission line to said lead.
40. The combination with a high potential transmission lines and insulator on a wood pole above said transmission lines and insulated from said pole, a ground lead extending from said ground wire in spaced relation to said pole, and flux control members connected with said transmission lines for reducing the tendency to discharge from said transmission lines to said ground wire and lead.
45. The combination with a high potential transmission line of a wood pole for supporting said line, an insulator for supporting said transmission line on said pole, a ground wire mounted on said pole and extending substantially parallel to said transmission line, a lead connected with said ground wire at a point thereon spaced away from said pole and extending downwardly past said transmission line, and a flux control device for distributing the flux in the electrostatic field adjacent said lead and transmission line to prevent discharge from said transmission line.
50. In combination, a support having a cross arm thereon, a high potential transmission line mounted on said cross arm at one side of said support, a ground wire mounted on said support substantially in alignment with the axis thereof and insulated by said support from ground, a lead connected with said ground wire at a point spaced from said support and extending downwardly to ground in spaced relation to said transmission line, and flux control members for preventing discharge from said transmission line and ground wire at the points thereof where said lead and transmission line are closest together.
55. In combination, a supporting pole of insulating material, a cross arm on said pole, high potential transmission lines carried by said cross arm at opposite sides of said pole, a ground wire mounted on said pole substantially in the plane thereof parallel with said transmission line, a lead connected with said ground wire at a point spaced from said pole and extending downwardly between said transmission lines, and a flux control device for controlling the field of force where said transmission lines and ground wire pass one another.
60. In combination, a wood pole, a cross arm on said pole, metallic bracing for said cross arm, insulators supported from said cross arm at opposite sides of said pole, high potential transmission lines supported by said insulators, an insulator mounted on said pole above said cross arm and between the vertical planes of said transmission lines, a conductor supported on said last-named insulator and extending parallel with said transmission lines, a ground lead connected with said conductor and extending downwardly between said transmission lines, said lead being spaced from said pole and extending downwardly between said transmission lines and having its lower end grounded, and means on said
